UNITED STATES PATENT OFFICE

170,849

RADIOPHONOGRAPH CABINET

Robert Davol Budlong, Skokie, Ill., and Jack De Young, Grand Haven, Mich., assignors to Zenith Radio Corporation, a corporation of Illinois

Application April 29, 1953, Serial No. 24,759

Term of patent 7 years

(Cl. D56—4)

To all whom it may concern:

Be it known that we, Robert D. Budlong, a citizen of the United States, residing at Skokie, in the county of Cook, State of Illinois, and Jack De Young, a citizen of the United States, residing at Grand Haven, in the county of Ottawa, State of Michigan, have invented a new, original, and ornamental Design for a Radio-Phonograph Cabinet, of which the following is a specification, reference being made to the accompanying drawings, forming a part thereof:

Figure 1 is a perspective view of a radio-phonograph cabinet embodying our new design with the phonograph compartment closed;

Figure 2 is another perspective view of the radio-phonograph cabinet with the above mentioned compartment opened;

Figure 3 is a fragmentary top plan view thereof.

The dominant features of this design reside in the portions shown by means of full lines in the drawing.

We claim:

The ornamental design for a radio-phonograph cabinet, substantially as shown and described.

ROBERT DAVOL BUDLONG.
JACK DE YOUNG.
